STAND ATTACHMENT FOR MUSICAL INSTRUMENTS

Victor Joseph Lawrence, Pittsburgh, Pa.

Application January 7, 1949, Serial No. 69,715

8 Claims. (Cl. 243—195)

1

My invention relates to stands for musical instruments such as guitars and the like for supporting them on a substantially horizontal surface at a predetermined angle to the erect position. It is an improvement in stand attachments disclosed in my co-pending application Serial No. 41,764, filed on July 31, 1948.

The improvement of my present invention over the previously disclosed one is generally that the bracket mounted on the musical instrument is shaped to form a pair of supporting legs represented by two protruding and sufficiently spaced apart heels to serve as a stand support and also carrying hingedly a foldable plate with two spreadable legs mounted thereon, together with positioning means for making these legs establish additional support areas spaced apart still further than those of the heels of the bracket and at suitable distance from them for establishing adequate support for, and insuring stable equilibrium of the instrument.

My present invention also obviates the drawbacks existing with conventional stands requiring slow and careful handling of the instrument when placing it on a separate conventional stand, the retention of the instrument on the conventional stand by gravity only, which is inadequate, the relative ease by which the instrument may be dislodged and toppled over from such a stand and the necessity of carrying the conventional stand separately and outside of the case of the instrument.

These and other drawbacks I discussed in more detail in my above mentioned pending application, hence it will not be necessary to elaborate on them here again. It should be sufficient to say that my present invention obviates these and other drawbacks by providing a stand attachment which is firmly securable to the instrument to be supported and in the folded position is protruding relatively little therefrom so that the instrument can be played conveniently while the stand attachment is fixed thereto, it can be folded and unfolded with ease by the player and placed, mounted on the instrument, with it in its case so that it need not be carried separately.

Hence one object of my invention is to provide a stand attachment for musical instruments such as guitars and the like which is firmly but releasably mounted on the instrument, has a mounting bracket of laterally sufficiently extending base portion constituting a pair of supporting legs of suitable stability and which carries hingedly mounted thereon a plate having spreadable legs and positioning means for operating them.

Another object is to provide a device of the character described in which a bracket, adapted to be secured to the instrument, hingedly carries a plate provided with two spreadable legs, guide

2

means for directing them into the desired positions, positioning means to operate them manually and stop means for limiting the end positions of the plate as well as those of the spreadable legs.

Another object is to provide an apparatus of the type set forth which is securely attachable to the instrument and foldable into the space in close proximity thereto so that the instrument may be played and/or stored in its case with the device mounted thereon.

Another object is to provide a stand attachment for musical instruments which has supporting legs equipped with resilient caps giving elastic and safe support to the instrument and guard against injury of the user.

Another object is to provide a stand attachment of simple construction, reliable operation which is inexpensive to manufacture.

The accomplishment of these and other objects will become clear when reading the following description in conjunction with the accompanying drawing in which

Fig. 1 is the vertical side view of the first embodiment of my invention chiefly in section, the stand attachment being shown in folded position fastened to a guitar broken away;

Fig. 2 is the elevational view of this first embodiment in folded position, as seen from the rear side that is toward the musician playing the instrument; the spreadable legs are also shown in dot and dash lines in spreaded position;

Fig. 3 is a side elevational view of the device attached to the instrument shown set up upon a substantially horizontal surface;

Fig. 4 is the plan view of the bracket alone as viewed from below.

Fig. 5 is the rear view partially in section, of the hinged plate and the spreadable legs mounted thereon as cut away from the bracket on broken line 5—5 in Fig. 1;

Fig. 6 is the partial side view, partly in section, of a modified form of the device in which the threaded fulcrum pin carrying the spreadable legs is lockable by a coacting nut;

Fig. 7 is the side view, partly in section, of another embodiment of the invention in which the device is attached to a musical instrument by means such as wood screws and is shown in erected position on a substantially horizontal surface; in dot and dash lines is indicated the contracted position of the spreadable legs as well in erect as in the folded positions;

Fig. 8 is a fragmental view, partly in section, of the detached bracket taken on line 8—8 in Fig. 7;

Fig. 9 is the front elevational view of this other embodiment in which the bracket is partially broken away and partially cut away on the broken line 9—9 in Fig. 7;

Fig. 10 is the rear elevational view of this device

in folded position the spreadable legs being shown in their spreaded position by dot and dash lines;

Fig. 11 is a partial sectional view of a modified spreadable leg having a circumferential groove and carrying a resilient cap shown to be made from rubber;

Fig. 12 is a partial sectional view of the modified spreadable leg and its resilient cap taken on line 12-12 in Fig. 11;

Fig. 13 is a partial sectional view of a bracket having a base portion with modified heel carrying a circumferential groove to retain the bead of a resilient cap shown to be made from rubber;

Fig. 14 is a sectional view taken on broken line 14-14 in Fig. 13.

Identical parts are designated by the same numerals throughout the several figures of the drawing.

Referring closer to Figures 1 to 5 illustrating the first embodiment of my invention, the bracket generally designated by 20 has an upright portion 22, sidewardly extending base portion 24 having two heels 26 protruding therefrom downwardly, and bottom portion 28 which is substantially perpendicular to base portion 24, and upright portion 22. As best seen in Fig. 4 bottom portion 28 carries a centrally disposed preferably open end slot 30. Bracket 20 is shown to be made from sheet material which may be metal, plastic, etc. It may be conveniently punched out of a sheet in form of a suitable blank the bottom portion 28 being formed by bending a corresponding extension of upright portion 22 at 90° in forward direction which is that toward the instrument to which it will be attached. The heels 26 are sufficiently spaced apart to define a base line of suitable length for safe support. The heels serve also the purpose to bridge over possible unevenness of the supporting surface. As best shown in Fig. 1 slot 30 accommodates attachment means such as screw 32 which is inserted in hole 34 conventionally provided in base beam 36 and bottom wall 38 of guitar 40 to be supported. Washers 42 of suitable resilient and relatively soft material such as fibre plastic, etc., serve to distribute the gripping pressure upon the instrument without crushing or injuring the affected portions thereof. Nut 44, shown to be a wing nut to dispense with the necessity of a wrench at the assembly, coacting with washer 46, fixes with sufficient frictional force the instrument 40 to bottom portion 28 of bracket 20 preferably in a position in which rear wall 41 of instrument 40 abuts liner 48. Liner 48, made from rubber, felt, leather, and the like elastic and relatively soft material, is fastened by any approved means such as rivets 50, shown, to bracket 20 and serves as padding to prevent any damage to the instrument which may result from fastening it to bracket 20. Bottom portion 28 and slot 30 are suitably dimensioned to accommodate a variety of instruments of different dimensions. Instead of rivets 50, liner 48 may be fastened to bracket 20 with screws, staples, suitable cement, adhesive layer, etc. Screw 32 is shown to be solid but it may be tubular to accommodate conductors (not shown) of an electric pickup device employed in so called "electric" guitars. Instead of screw 32 a stud with a suitable nut may also be employed.

Fixed to, or integral with, the upper region of upright portion 22 and protruding therefrom rearwardly are lugs 52 carrying fulcrum pin 54 retained by conventional means such as cotter pin 56 for oscillatably mounting plate 58 that has fixed thereto, or integral therewith, cam 60 on its

upper central portion. At its lower region plate 58 carries two stirrups substantially symmetrically disposed to its center line and suitably spaced apart.

As best seen in Fig. 1 cam 60 has operative surfaces 64, 66 and 68 in suitable angular and dimensional relationship. Flat spring 70 fixed to upright portion 22 by any approved means such as rivets 72, shown, has suitable shape to coact with surface 64 of cam 60 in folded position of plate 58 tending to retain it in this position in which it is substantially parallel to upright portion 22.

As shown in Fig. 3 spring 70 also coacts with surface 66 and retains it resiliently after plate 58 (and with it cam 60) is turned by a predetermined angle rearwardly at which angle surface 68 contacts upright portion 22 of bracket 20 positively stopping its further rearward oscillation.

Plate 58 is provided with central slot 74 extending from the upper region of plate 58 to its lower region in which slot pin 76 is slidably reciprocably accommodated. Pin 76 oscillatably carries two spreadable legs 78 and has at both ends suitable heads 80 and 82 having appropriate shoulders 84 and 86 for retaining pin 76 and with it legs 78 at all times in sliding contact with plate 58. The head 80 at the rear end of pin 76 is preferably shaped as a knob shown to be riveted to pin 76 and having shoulder 84 reaching over the width of slot 74 slidably contacting plate 58. The head 82 at the front end of pin 76 is preferably disk-shaped forming shoulder 86 slidably contacting one of the spreadable legs 78. Fixed to the head 82 and protruding toward the front therefrom is a stop member shown to be spherically ended dog 88 made of relatively resilient, compressible, vibration and sound absorbing material, such as rubber, impregnated fabric, felt, fibre, plastic, etc. Each of the spreadable legs 78 is milled to half thickness adjacent to fulcrum pin 76 so that they may be oscillated on each other when both are in sliding contact with plate 58.

Upright portion 22 is provided with an aperture 90 of suitable shape and location for snugly receiving and by friction retaining therein dog 88 when plate 58 is in folded position and knob 80 is in, respectively close to its top position. The spreadable legs 78 are retained at all times in sliding contact with plate 58 by pin 76 and by stirrups 62.

The first embodiment operates as follows:

For fastening the stand attachment to a musical instrument, such as a guitar 40, screw 32 carrying washer 42 is inserted into hole 34 of the guitar 40 and bracket 20 with its upright portion 22 and liner 48 is placed adjacent to the central lower portion of the rear wall 41 of the instrument so that the threaded end of screw 32 with loosened wing nut 44 protrudes through washer 42, liner 48, slot 30 and washer 46 from bottom portion 28 of bracket 20. Subsequently wing nut 44 is tightened developing suitable friction between the instrument, the washers, the liner and bottom portion 28 to fix the bracket 20 securely to the instrument during use as well as storage thereof in its case.

To place the attachment in folded position, the operator, holding with one hand the instrument, pushes with his other hand knob 80 close to its top position shifting spreadable legs upwardly substantially within the projection of plate 58 and simultaneously swinging plate 58 into parallel alignment with upright portion 22 of bracket

20. Dog 88, due to the guiding effect of its rounded end portion, is pressed into aperture 90 in which it is retained by friction and also by the urge of spring 70 contacting flat surface 64 of cam 60 and resiliently opposing oscillation of plate 58.

To place the device in unfolded position, ready to support the instrument on a substantially horizontal surface such as the floor, podium, stage, shelf, etc., the operator gets hold of knob 80 pulls it rearwardly oscillating the plate 58 against the resilient retaining force of spring 70 out of the parallel and into an angular position relative to upright portion 22 as determined by surface 68 of cam 60 that contacts the rear surface of upright 22 limiting the rearward swing of plate 58. Simultaneously dog 88 emerges from aperture 90 and the operator now slides knob 80 downwardly causing legs 78 to spread due to the guiding action of slot 74 and stirrups 62.

Spring 70 contacts surface 66 of cam 60 resiliently retaining plate 58 in its unfolded position, ready to be lowered to the supporting surface to be held thereon in stable equilibrium as the substantially quadrilateral base offered by heels 26 and spreaded legs 78 is large enough to include, with suitable leverage against overturning, the vertical projection of the center of gravity of the combined instrument and stand. The weight of the instrument urging the legs 78 into their outermost spreaded position as determined by their contact points with stirrups 62 and the end of central slot 74 forming a downward stop for pin 76 will retain legs 78 in their spreaded position.

Fig. 6 shows a modification of the first embodiment of my invention consisting in employing screw 92 to fulcrum spreadable legs 78. Screw 92 has a threaded end portion and prismatic or flattened portion 94 that slidably fits into slot 74 preventing turning and head 96 to which dog 88 is rigidly fastened. Wing nut 98 coacts with threaded portion of screw 92 and serves to tighten spreadable legs 78 to plate 58 by friction selectively in their folded, respectively spreaded positions constituting an added means for locking legs 78. Washer 99 (shown in dot and dash lines), preferably of material having high frictional coefficient, may be inserted between wing nut 98 and plate 58 for added security.

The operation of this modified form is substantially the same as that of the first embodiment except that wing nut 98 is released and tightened before, respectively after, setting spreadable legs 78.

Figures 7 to 10 show another embodiment of my invention.

As best shown in Figures 7 and 8, the bracket, generally designated by 100, has upright portion 102, base portion 104 sidewardly protruding therefrom carrying downwardly extending spaced apart heels 106, and bottom portion 108 which is substantially perpendicular to upright portion 102 abutting forwardly therefrom and is provided with suitable attachment means such as holes 109 and screws 110 to fasten it to the instrument 112.

Lugs 52, rigidly fixed to, or integral with, and rearwardly protruding from upright portion 102 carry fulcrum pin 54 locked by cotter pin 56 oscillatably mounting plate 114 which has at its top region cam 116. This cam is fixed to, or integral with, plate 114 and has three operative surfaces 118, 120 and 122 in suitable angular and dimensional relationship for coaction with resilient

means such as flat spring 124 and with a rearward surface of upright portion 102 as herein-after described in detail.

Spring 124 is rigidly attached to upright portion 102, by any approved means such as rivets 123, shown. Aperture 125 in upright 102 admits part of spring 124 to reduce the space needed for the device. A central slot 74 extends from the upper to the lower region of plate 114 and reciprocably mounts pin 126 that oscillatably carries two spreadable legs 128 and has a preferably flat head 130 at one end and knob 132 at its other end limiting spreadable legs 128 into sliding contact with plate 114. One of legs 128 is suitably bent.

Plate 114 has two pairs of outer and inner apertures in its lower region which are suitably spaced apart and the developed blanks of which are shown in dot and dash lines on the right hand side of Fig. 9. Each pair of the apertures consists of one substantially U-shaped outer aperture 134 surrounding from 3 sides an inner aperture 136 that equals substantially the cross sectional area of one spreadable leg 128. The two flaps determined by the outer apertures are bent forwardly at 90° at the line between the end points of the legs of the U-shaped outer apertures 134 so that the inner apertures 136 admit the spreadable legs when they slidably contact plate 114 thereby serving as guides for the legs.

The fulcrum pin 126 is shown to be the same type as 76 of the first embodiment (but may be of the type 92 to 98 shown in Fig. 6) for mounting spreadable legs 128 oscillatably. As best seen in Fig. 10 the upright portion 102 carries stop 138 which is made preferably of resilient, sound- and vibration absorbing material, such as rubber, plastic, felt, impregnated fabric, etc., having suitable shape to be wedged with resilient pressure the space between the spreadable legs in their folded or upper position pressing them against the outer sides of inner apertures 136 preventing their vibration and rattling. Stop 138 is rigidly fixed to upright portion 102 by any approved means of attachment, such as by rivets 139, shown. Stop 138 acts as a cushion and I refer to it also as such.

Resilient, relatively soft liner 133, made of rubber, felt, fabric, plastic, etc., is interposed between musical instrument 112 and bracket 100 and is attached to upright portion 102 by suitable means, such as rivets 135 and carries suitable holes for appropriate attachment elements such as wood screws 110 fixing the bottom portion 105 of bracket 100 to instrument 112.

This embodiment operates in the same manner as the first one except that the instrument is attached by screws 110 to bottom portion 105 of bracket 100 and the spreadable legs 128 in their folded position are forced with slight pressure upon resilient stop or cushion 138.

Figures 11 and 12 are cross sectional views of a modified form of spreadable legs designated by 140 each leg carrying at its end portion a circumferential groove 142 mounting bead 144 of resilient cap 146 which may be made of rubber, rubberized fabric, etc. for elastically supporting the stand, absorbing sound and vibration, increasing the friction to prevent slipping and for preventing injury to the operator during handling.

Cap 146 has somewhat smaller inner dimensions than the corresponding ones of legs 140 so that the caps are expanded during mounting and exert resilient compression upon the legs on which the caps are retained by friction and also by bead 144 occupying groove 142.

Figures 13 and 14 are cross sectional views of the heels of a modified base portion, designated by 148, of a bracket. Heels 150 have each a circumferential groove 152 for engaging bead 154 of resilient cap 156 which is of similar material and has the same action and purpose than those of previously described cap 146.

Having described and illustrated preferred embodiments of my invention it will be understood that several changes and modifications may be made without departing from the spirit and scope of my invention, hence I do not intend to be limited by these illustrative embodiments but only by the appended claims.

What I claim as new and desire to protect by Letters Patent is:

1. A bracket having liner means to prevent wearing of the object to which it is attached, attachment means releasably fixing said bracket to said object, a plate oscillatably attached to said bracket, a plurality of spreadable legs on said plate, positioning means thereon, guide means on said plate keeping said legs in sliding contact with said plate, and stop means acting upon said legs limiting their motion in folded as well as in spreaded position, said bracket having an upright portion, a base portion crosswise extending therefrom carrying two spaced apart, downwardly protruding heels, and a slotted bottom portion perpendicularly disposed thereto, and said positioning means including a central slot running in up-and down direction in said plate, and a fulcrum pin oscillatably mounting said legs and reciprocably arranged in said slot.

2. A bracket having liner means to prevent wearing of the object to which it is attached, attachment means releasably fixing said bracket to said object, a plate oscillatably attached to said bracket, a plurality of spreadable legs on said plate, positioning means thereon, guide means on said plate keeping said legs in sliding contact with said plate and stop means acting upon said legs, limiting their motion in folded as well as in spreaded position, said bracket having an upright portion, a base portion crosswise extending therefrom carrying two spaced apart, downwardly protruding heels, and a slotted bottom portion perpendicularly disposed thereto, and said positioning means including a central slot running in up-and down direction in said plate, a fulcrum pin oscillatably mounting said legs and reciprocably arranged in said slot, said guide means including two stirrups rigidly fixed to the bottom region of said plate protruding therefrom sufficiently to encircle free fittingly each one of said legs, and said stop means including a dog fixed to said fulcrum pin and a correspondingly shaped aperture suitably located in said upright portion retaining said dog in the folded position of said plate when said legs are in contracted position.

3. A bracket having liner means to prevent wearing of the object to which it is attached, attachment means releasably fixing said bracket to said object, a plate oscillatably attached to said bracket, a plurality of spreadable legs on said plate, positioning means thereon, guide means on said plate keeping said legs in sliding contact with said plate and stop means acting upon said legs limiting their motion in folded as well as in spreaded position, said bracket having an upright portion, a base portion crosswise extending therefrom carrying two spaced apart, downwardly protruding heels, and a slotted bottom portion perpendicularly disposed thereto and said posi-

tioning means including a central slot running in up-and down direction in said plate, a fulcrum pin oscillatably mounting said legs and reciprocably arranged in said slot, said guide means including two flaps substantially perpendicularly protruding from the bottom region of said plate and each containing an aperture free fittingly encircling one of said legs, and said stop means including a cushion fixed to said upright portion and adapted to be wedged between said legs in their contracted position when said plate is folded toward said upright portion.

4. A bracket having liner means to prevent wearing of the object to which it is attached, attachment means releasably fixing said bracket to said object, a plate oscillatably attached to said bracket, a plurality of spreadable legs on said plate, positioning means thereon, guide means on said plate keeping said legs in sliding contact with said plate and stop means acting upon said legs limiting their motion in folded as well as in spreaded position, said bracket having an upright portion, a base portion crosswise extending therefrom carrying two spaced apart, downwardly protruding heels, and a bottom portion perpendicularly disposed thereto, and said positioning means including a cam fixed to said plate, a spring fixed to said bracket and coacting with suitable surface portions of said cam for resiliently retaining it in folded and in unfolded positions, respectively, of said plate, a central slot running in up-and down direction in said plate, and a fulcrum pin reciprocably arranged in said slot and oscillatably mounting said legs.

5. A bracket having liner means to prevent wearing of the object to which it is attached, attachment means releasably fixing said bracket to said object, a plate oscillatably attached to said bracket, a plurality of spreadable legs on said plate, positioning means thereon, guide means on said plate keeping said legs in sliding contact with said plate and stop means acting upon said legs limiting their motion in folded as well as in spreaded position, said bracket having an upright portion, a base portion crosswise extending therefrom carrying two spaced apart, downwardly protruding heels, and a bottom portion perpendicularly disposed thereto, said positioning means including a cam fixed to said plate, a spring fixed to said bracket and coacting with suitable surface portions of said cam for resiliently retaining it in folded and in unfolded positions, respectively, of said plate, a central slot running in up-and down direction in said plate, and a fulcrum pin reciprocably arranged in said slot and oscillatably mounting said legs, said guide means including two stirrups rigidly fixed to the bottom region of said plate protruding therefrom sufficiently to encircle free fittingly each one of said legs and said stop means including a dog fixed to said fulcrum pin and a correspondingly shaped aperture suitably located in said upright portion retaining said dog in the folded position of said plate when said legs are in contracted position.

6. A bracket having liner means to prevent wearing of the object to which it is attached, attachment means releasably fixing said bracket to said object, a plate oscillatably attached to said bracket, a plurality of spreadable legs on said plate, positioning means thereon, guide means on said plate keeping said legs in sliding contact with said plate and stop means acting upon said legs limiting their motion in folded as well as in spreaded position, said bracket having

an upright portion, a base portion crosswise extending therefrom carrying two spaced apart, downwardly protruding heels, and a bottom portion perpendicularly disposed thereto, said positioning means including a cam fixed to said plate, a spring fixed to said bracket and coacting with suitable surface portions of said cam for resiliently retaining it in folded and unfolded positions, respectively, of said plate, a central slot running in up-and down direction in said plate, and a fulcrum pin reciprocably arranged in said slot and oscillatably mounting said legs, said guide means including two flaps substantially perpendicularly protruding from the bottom region of said plate and each containing an aperture free fittingly encircling one of said legs, said stop means including a cushion fixed to said upright portion and adapted to be wedged between said legs in their contracted position when said plate is folded toward said upright portion.

7. A bracket having liner means to prevent wearing of the object to which it is attached according to claim 2 in which said heels and legs

are provided each with a resilient end-cap having relatively high frictional coefficient for providing elastic support and preventing slipping of the device and injury to the operator.

8. A bracket having liner means to prevent wearing of the object to which it is attached according to claim 3 in which said heels and legs are provided each with a resilient end-cap having relatively high frictional coefficient for providing elastic support and preventing slipping of the device and injury to the operator.

VICTOR JOSEPH LAWRENCE.
